UNITED STATES PATENT OFFICE.

GEORGE W. COOK, OF MENOMONIE, WISCONSIN.

CHANGEABLE EXHIBITOR.

1,204,135.

Specification of Letters Patent. Patented Nov. 7, 1916.

Application filed January 26, 1916. Serial No. 74,407.

To all whom it may concern:

Be it known that I, GEORGE W. COOK, a citizen of the United States, residing at Menomonie, in the county of Dunn and State of Wisconsin, have invented certain new and useful Improvements in Changeable Exhibitors, of which the following is a specification, reference being had to the accompanying drawings.

10 This invention relates to certain improvements in changeable exhibitors and has relation more particularly to a device of this general character especially designed and adapted for advertising purposes, and it is 15 an object of the invention to provide a device of this general character including a rotatably supported exhibiting device traveling in a predetermined path, and whereby said exhibiting device is intermittently rotated at predetermined intervals.

20 It is also an object of the invention to provide a device of this general character having novel and improved means whereby a carrier is caused to travel in a predetermined path, and wherein said carrier is provided with a rotatably supported exhibiting device adapted to be partially rotated at predetermined points along the path of travel of the carrier, and whereby said exhibiting device is normally locked against 25 rotation.

Furthermore the invention has for its object to provide a novel and improved device of this general character including a carrier 35 movable in an angular path and provided with an intermittently rotated exhibiting device together with means whereby the carrier is held against rotary movement when the course of its travel is changed.

40 The invention consists in the details of construction and in the combination and arrangement of the several parts of my improved exhibitor whereby certain important advantages are attained and the device is 45 rendered simpler, less expensive and otherwise more convenient and advantageous for use, all as will be hereinafter more fully set forth.

The novel features of the invention will 50 hereinafter be definitely claimed.

In order that my invention may be the better understood, I will now proceed to describe the same with reference to the accompanying drawings, wherein—

55 Figure 1 is a view partly in elevation and

partly in section illustrating a changeable exhibitor constructed in accordance with an embodiment of my invention; Fig. 2 is a view in top plan of the device as illustrated in Fig. 1; Fig. 3 is an enlarged detail 60 sectional view taken transversely through one of the side members of the frame and through a carrier and its concomitant parts, as herein embodied; Fig. 4 is a view partly in elevation and partly in section of one of 65 the carriers as herein disclosed, the outer plate being omitted; Fig. 5 is an elevational view of the fixed disk as herein set forth; Fig. 6 is an elevational view of the rotatable disk as herein included; Fig. 70 7 is a sectional view taken substantially on the line 7—7 of Fig. 3; and Fig. 8 is a sectional view taken substantially on the line 8—8 of Fig. 3.

As disclosed in the accompanying drawings, F denotes a frame substantially rectangular in form and having its members 1 substantially U-shape in cross section with the free longitudinal marginal portions of the side walls of each of the members provided with the inturned flanges 2, affording a track-way T in which travel the carriers C. The carriers C are caused to travel along the track-way T through the medium of the endless chain 3, in a manner to be herein 75 after more particularly referred to, said chain being disposed around the guide sprockets 4 operatively supported by the frame F inwardly of the track-way T at the corners thereof. One of the sprockets 80 4 is adapted to be operatively engaged, as indicated at 5, with a suitable source of power, whereby the requisite movement may be imparted to the chain. As the carriers 90 C and their concomitant parts are in duplication, it is thought that a description of one will suffice for the purposes of disclosure.

As herein set forth, each of the carriers C comprises the superimposed rectangular plates 6 of a diameter in excess of the width 100 of the track-way T and separated one from the other by the interposed rectangular plate 7 of a diameter substantially equal to the width of the track-way T, the plates 6 overlying the opposite faces of the flanges 2 for 105 a purpose which is believed to be self-evident.

The plates 6 and 7 have disposed through their axial centers the stub shaft 8, the inner end of which has produced in its axial center 110

the recess 9 adapted to be engaged by the pin 10 affording a pivotal connection with the substantially triangular plate 11, the base of which coacts with the inner wall of 5 the members 1 and with the apex thereof operatively engaged with the chain 3.

It is to be noted that the pin 10 is positioned on the plate 11 a distance away from the point of connection between the plate 11 10 and the chain 3 equal to the radius of each of the sprockets 4, so that the carrier C is pulled absolutely or snugly into the corner of the track-way T when the plate 11 turns over the surface of a sprocket 4. By this arrangement it will be seen that the pin 10 at 15 all times remains at a dead center so that the carrier C in making a turn in the track-way T does not rotate, and therefore always remains in the same position. The stub shaft 20 8 is non-rotatably engaged with the plates 6 and 7 and extends a predetermined distance in advance of the outer plate 6 and terminates in the reduced threaded portion 12, to which is fixed the disk 14 having a sector 25 of 90° cut out, as indicated at 15, to afford a visual opening as will presently be apparent.

Loosely mounted upon the shaft 8 intermediate the outer plate 7 and the disk 14, is the sleeve 16 having its opposite ends provided with the annular flanges 17 and 18, the inner flange 17 being provided with the radially disposed outstanding fingers or pins 19 arranged in equi-distantly spaced relation, and as herein embodied, four in number. The pins 19 are adapted to engage the trips 20 suitably positioned upon the frame F whereby it will be perceived that as a pin 19 contacts with a trip 20, the sleeve 16 will be given a quarter turn so that the matter to 40 be exhibited arranged on the outer face of the disk 21 exposed through the opening 15, may be changed, as said disk 21 is suitably secured to the outer face of the annular flange 18. As is clearly illustrated in the 45 accompanying drawings, the outer face of the disk 21 is radially divided into four fields 22, to each of which differing matter to be exhibited may be arranged.

The sleeve 16 is normally held against rotation about the shaft 8 through the medium of the clutch ball 23 arranged within the radial opening 24 formed in the outer annular flange 18 and in communication with the bore of the sleeve 16 and which is adapted to 50 be forced through the medium of the expansible member 25 into one of the four equi-distantly spaced recesses 26, arranged in an annular series in the periphery of the shaft 8. In practice, it is preferred that the 55 recesses 26 be arranged in planes radiating from the shaft 8 in longitudinal alinement, relative to the shaft 8 and the radial planes occupied by the fingers or pins 19. As herein embodied, the expansible member 25 comprises a conventional coil spring and is in- 60

terposed between the ball 23 and the cap or set screw 27 threaded in the outer end of the opening 24. I also find it of advantage to provide the outer disk 14 with a shelf 28 on which an article of merchandise may be 70 positioned for display, or if preferred an article of merchandise or other article may be secured directly to the outer face of the outer disk 14.

From the foregoing description, it is 75 thought to be obvious that an exhibitor constructed in accordance with my invention is of an extremely simple and comparatively inexpensive nature and is particularly well adapted for use by reason of the convenience 80 and facility with which it may be assembled, and it will also be obvious that my invention is susceptible of some change and modification without material departure from the principles and spirit thereof and for this 85 reason I do not wish to be understood as limiting myself to the precise arrangement and formation of the several parts herein shown in carrying out my invention in practice. 90

I claim:

1. A device of the character described comprising a frame provided with an endless track-way, a carrier coacting with said track-way, means for imparting movement 95 to the carrier, a shaft projecting outwardly from the carrier, a disk rotatably mounted on the carrier, a second disk fixed to the shaft in advance of the first named disk, said second named disk having a portion 100 cut out to afford a visual opening and means coacting with the movable disk for intermittently rotating the same.

2. A device of the character described comprising a frame provided with an endless track-way, a carrier coacting with said track-way, means for imparting movement to the carrier, a shaft projecting outwardly from the carrier, a disk rotatably mounted on the carrier, a second disk fixed to the 105 shaft in advance of the first named disk, said second named disk having a portion cut out to afford a visual opening and means coacting with the movable disk for intermittently rotating the same, and means for 110 normally maintaining the rotatable disk against rotation about the shaft.

3. A device of the character described comprising a frame provided with a track-way, a carrier coacting with the track-way, 115 means for imparting movement to the carrier, a shaft carried by the carrier and extending in advance thereof, a sleeve rotatably mounted upon the carrier, means for normally holding the sleeve against rotation, fingers radiating from the sleeve, a trip carried by the frame adapted to engage the fingers of the sleeve for partially rotating the sleeve, a disk carried by the outer end of the sleeve, and a second disk fixed to 120 125 130

the shaft in advance of the sleeve and having a portion thereof cut out to afford a visual opening.

4. A device of the character described comprising a frame including angularly related members, each of said members being substantially U-shape in cross section and having their side walls provided with in-turned flanges to afford a track-way, a carrier coacting with the track-way, a shaft supported by the carrier, a plate pivotally engaged with the inner end of the shaft and having a straight edge coacting with the inner wall of each of the members, an endless chain adapted to travel within the members, 30 guide sprockets carried by the members at the corners of the track-way, said plate being operatively connected with the chain, the connection between the shaft and the plate being at a point on the plate spaced 35 from the operative connection between the plate and the chain a distance equal to the radius of the sprockets, the carrier including plates overlying the opposite faces of the inturned flanges. 40
5. A device of the character described comprising a frame including angularly related members, each of said members being 45

substantially U-shape in cross section and having their side walls provided with in-turned flanges to afford a track-way, a carrier coacting with the track-way, a shaft supported by the carrier, a plate pivotally engaged with the inner end of the shaft and having a straight edge coacting with the inner wall of each of the members, an endless chain adapted to travel within the members, 30 guide sprockets carried by the members at the corners of the track-way, said plate being operatively connected with the chain, the connection between the shaft and the plate being at a point on the plate spaced 35 from the operative connection between the plate and the chain a distance equal to the radius of the sprockets, the carrier including plates overlying the opposite faces of the inturned flanges. 40

In testimony whereof I hereunto affix my signature in the presence of two witnesses.

GEORGE W. COOK.
